UNITED STATES PATENT OFFICE

2,063,062

SUCTION CLEANER

Charles H. Sparklin, Chicago, Ill., assignor to
Birtman Electric Company, Chicago, Ill., a corporation of Illinois

Application October 10, 1935, Serial No. 44,432

8 Claims. (Cl. 15—16)

This invention relates to improvements in suction cleaners and, more especially, to that type of cleaner provided with a nozzle that is vertically adjustable with respect to the surface of the material being cleaned.

It is well known that suction cleaners of the type here under consideration are most generally used for cleaning rugs, carpets and the like, although, of course, they are also used for cleaning bare hardwood floors, linoleum and other surfaces. In connection with the cleaning of carpets, however, materials of varying thickness and softness are encountered; and, consequently, it has been found advisable to provide the cleaner with a vertically adjustable nozzle so that when operating on a carpet that is relatively thick and soft where the wheels sink in to a relatively great extent, the nozzle can be vertically adjusted upwardly so that in the cleaning of such carpet, the mouth of the nozzle will not be too close to the fabric or bear too much thereon. Contrariwise, when operating upon a thin hard carpet or on a bare floor, or linoleum, or the like, where the wheels do not sink in to any perceptible extent, it has been found advisable to adjust the nozzle vertically downwardly so that it will be in proper position with respect to the surface being cleaned. Likewise, in operating upon carpets of this thickness, it has been found that vertical adjustment of the nozzle is necessary or desirable.

The principal feature of my invention is the provision of means for automatically adjusting the nozzle, depending upon the character of the material being cleaned.

In general, it may be stated that this is accomplished by providing a pilot, in the nature of a relatively light member that will "float" on the surface of the material being cleaned. One or more of the wheels of the cleaner, however, will sink into the material to a certain extent below its surface, depending upon the nature of the material itself. I also provide means for vertically adjusting the nozzle and power means for operating said adjusting means. I also provide a connection between the pilot and the power means whereby the power means will be operated under control of the pilot so that the nozzle will be adjusted vertically by and in accordance with the movements of said pilot. In other words, there will always be an automatic adjustment of the nozzle to the proper height, depending upon the character of the material being cleaned and the extent to which the sup-

porting wheels of the cleaner sink into such material below its surface.

Other features and advantages of my invention will appear more fully as I proceed with my specification.

In that form of device embodying the features of my invention shown in the accompanying drawings—

Figure 1 is a view in side elevation, partly in section; Fig. 2 is a fragmentary top plan view; Fig. 3 is a bottom plan view; Fig. 4 is a view taken as indicated by the line 4—4 of Fig. 1; Fig. 5 is a view in perspective of the pilot member and the adjacent wheel; Fig. 6 is a wiring diagram; and Figs. 7 and 8 are diagrammatic views.

Cleaners with vertically adjustable nozzles of various types have heretofore been made in which means are provided for vertically adjusting the nozzle with respect to the carriage, depending upon the thickness, character and type of surface being cleaned. Various means have been provided also for manually effecting such adjustment. It is to be understood that my invention may be used in virtually any form of such cleaner. That is, the particular means provided for adjusting the nozzle may have a variety of forms. The principal feature of my invention is the automatic control of said adjusting means by a pilot floating on the surface of the material being cleaned so that the nozzle will always be automatically adjusted by and in accordance with the extent of sink of one or more wheels of the cleaner into the material below its surface or by and in accordance with relative movement of said pilot with respect to one of the supporting wheels of the cleaner, or by and in accordance with the character, thickness, or softness of the material being cleaned.

As shown in the drawings, the cleaner may be of a conventional type supported by two front wheels 10, 10^a and two rear wheels 11, 11^a. The nozzle is indicated by 12. As here shown, vertical adjustment of the nozzle is effected by raising or lowering the rear wheels 11, 11^a. This pivots the entire cleaner on the axis 13 of the front wheels to raise or lower the mouth 12^a of the nozzle 12. As here shown, adjustment of the rear wheels 11, 11^a is effected by means of the screw 14 operating in a worm wheel 15 controlled by the worm 16 on the shaft of the reversible motor 17. The lower end of the screw 14 is pivotally attached at 14^a to the arm 18 carrying one of the rear wheels 11, said arm being pivoted at 20. Rotation of the worm 16 by the reversible motor 17 will rotate the worm wheel 15 to raise or

lower the screw 14 to raise or lower the wheels 11, 11 to vertically adjust the nozzle 12.

The pilot member is indicated by 25 and is utilized for measuring the degree of sink of one of the wheels to thus control operation of the motor 17 to effect the necessary vertical adjustment of the nozzle. It is preferable, of course, to control the nozzle by the sink of one of the front wheels, since they ordinarily carry more weight than the rear wheels. It is also desirable to place the pilot in close proximity to one of these front wheels as this will give a truer measurement of the actual sink of the wheel into the material below its surface. One of the wheels and the pilot member or float is shown in perspective in Fig. 5. 10 indicates the wheel, the pilot member being in the shape of a cylindrical shell of light thin sheet metal, indicated by 25. This shell is pivoted at 26, 26 in the fork 27 carried by the cleaner and 20 has a portion cut away, as indicated at 28, to accommodate the support 29 for the wheel 10. The pilot is large enough so that it is free to move up and down relative to the wheel. 30 indicates a light spring preferably employed to hold the pilot 25 down on the surface of the material being cleaned. This spring is very light, however, and the pilot itself is very light in weight so that it will "float" substantially on the surface of the material being cleaned. That is, it will sink into 30 the material only to a very small extent, if at all, and not nearly as much into soft material as the wheel 10 will sink. It is to be noted, also, that the lower surface of the pilot 25, as indicated by 25a, being cylindrically curved will slide easily 35 over the surface of the material being cleaned with little or no tendency to sink down into such surface. It will be seen also that the lower edge of the pilot that appears on the surface being cleaned has considerable width, thus giving at 40 least a line contact of considerable length and, in all probability, a surface contact of considerable area, thus preventing the pilot from sinking into the surface of even soft thick carpets to any perceptible extent. As here shown, the spring 45 30 is connected to an ear 31 on the pilot at one end, the other end of the spring being connected to a suitable lug 32 carried by the cleaner.

The pilot 25 is provided with an ear 33 at the top to which is pivotally connected the bar 34 having a pivoted extension 34a carrying a bar 35 with the two contacts 36 and 37. See Figure 6. This bar 35 is slidably mounted in a slideable switch box 38 carrying the contacts 39, 40, 41 and 42. As has been stated, the switch box 38 is itself slideable and carried on the end of a screw 43 in the bevel gear 44. The latter meshes with another bevel gear 45 on the lower end of the shaft 46 carrying the worm wheel 47 which also is operated by the worm 16 on the motor 60 shaft. See Figure 7.

A general description of the operation of the device will be helpful in understanding the invention. The reader is referred particularly to Figures 6 and 7. It may be stated generally that the reversible motor 17 is supplied with power from the lines 50. The motor is series wound, 51 indicating the armature and 52, the field. It will be seen from the wiring diagram of Figure 6 that the direction of current through the field 52 will 65 be reversed, depending upon whether contacts 39 and 40 are connected or contacts 41 and 42. The member 35 connects the contacts 36 and 37 to form a bridging member. It will be seen, therefore, that movement of the bridging member 35 to the right (as viewed in Figure 6) will connect

contacts 41 and 42 to operate the motor in one direction, whereas its movement to the left to connect the contacts 39 and 40 will operate the motor in the reverse direction. When it is in the mid position, as shown in Fig. 6, the motor will not operate at all. It will be seen also, especially by reference to Figure 7, that rotation of the motor 16 not only raises or lowers the back wheels, but also, operating through the worm wheel 47, bevel gears 45 and 44 and screw 43, will move 10 the switch box 38 carrying the contacts 39, 40, 41 and 42. The parts are so connected and proportioned that movement of the pilot will slide the extension 34 to cause the bridging member 35 to start the motor in one direction or the other, depending upon whether the pilot moves upwardly or downwardly relatively to the adjacent wheel 10. This will start operation of the motor 17 to commence to effect the desired adjustment of the nozzle and this operation of the 20 motor, as above described, will also move the switch box 38 to break the contact made by the bridging member 35. If the pilot member continues to move, of course, the motor will continue to operate. When the pilot no longer continues 25 to move, it will be seen that the member 35 will no longer make contact and the motor will, therefore, stop, leaving the nozzle 12 in the correct position. It is to be understood that the bridging member is adapted to make sliding contact 30 with the contact points 39, 40, 41 and 42, as shown in Figs. 7 and 8, so as to permit some extra movement of the bridging member after contact is first made. After contact is made, the box will be moved in the same direction by operation of 35 the motor, such movement continuing over the sliding contacts until the contacts are completely broken, whereupon the motor will stop. Consequently, the motor will continue to operate until the box 38 has moved far enough to break the contact. The motor will then stop, leaving the nozzle 40 adjusted at the correct height for the position of the pilot with respect to the wheel.

In general, it may be stated that up and down movement of the pilot with respect to the wheel 45 10 will cause the bridging member 35 to make contact to cause operation of the motor 17 to adjust the nozzle upwardly or downwardly and far enough until the bridging member 35 is not making contact at either side, at which point 50 operation of the motor 17 will stop and leave the nozzle adjusted to the correct height.

The operation of the pilot is shown in Fig. 4, where a rather thick soft carpet is indicated by 137. That is, the carpet has a rather thick pile. 55 It will be seen that the wheel 10 is sinking into the carpet below its surface to a considerable extent, while the pilot 25 is riding or floating substantially on the surface. By the "surface" is meant the very top of the fabric. Thus the pilot 25 is resting substantially on the upper ends of the threads forming the pile without bending them over or crushing them down to any considerable extent. As stated, however, the wheel 10 sinks down into the carpet below its topmost surface 65 to a considerable extent and the extent of this sink of the wheel 10 with respect to the vertical position of the pilot 25 is what controls operation of the motor 17 to adjust the nozzle to the requisite height.

While I have shown and described certain embodiments of my invention, it is to be understood that it is capable of many modifications. Changes, therefore, in the construction and arrangement may be made without departing from 70

the spirit and scope of the invention as disclosed in the appended claims, in which it is my intention to claim all novelty inherent in my invention as broadly as permissible, in view of the prior art.

5. What I claim as new, and desire to secure by Letters Patent, is:

1. In combination with a suction cleaner having supporting wheels and a nozzle vertically adjustable with respect to the surface of the material 10 being cleaned, means for automatically adjusting said nozzle by and in accordance with the degree of sink of one of said wheels into said material below its surface.
2. In combination with a suction cleaner having 15 supporting wheels and a nozzle vertically adjustable with respect to the surface of the material being cleaned, motor means for adjusting said nozzle, motor controlling means operated by the degree of sink of one of said wheels into the material 20 below its surface, and a connection between said motor means and said motor controlling means whereby the nozzle is automatically adjusted by and in accordance with the degree of sink of said wheel.
- 25 3. In combination with a suction cleaner having supporting wheels and a nozzle vertically adjustable with respect to the surface of the material

being cleaned, a pilot adapted to float substantially on the surface of the material being cleaned, motor means for vertically adjusting the nozzle, and means for controlling said motor means by and in accordance with the relative vertical movement of said pilot and said wheels.

4. In combination with a suction cleaner having supporting wheels and a nozzle vertically adjustable with respect to the surface of the material being cleaned, a pilot adjacent one of said wheels 10 adapted to float substantially on the surface of the material being cleaned, motor means for vertically adjusting the nozzle, and means for controlling said motor means by and in accordance with relative vertical movement of said pilot and 15 said wheels.

5. Apparatus as claimed in claim 3, in which the pilot is provided with a curved lower surface.

6. Apparatus as claimed in claim 4, in which the pilot is provided with a curved lower surface. 20

7. Apparatus as claimed in claim 3, in which the pilot is substantially cylindrical.

8. Apparatus as claimed in claim 4, in which the pilot is substantially cylindrical and partially surrounds said wheel. 25

CHARLES H. SPARKLIN.
